UNITED STATES PATENT OFFICE.

CLARENCE E. GRIFFITH, OF WRIGHTS, ILLINOIS.

WRENCH.

1,098,569.

Specification of Letters Patent.

Patented June 2, 1914.

Application filed October 11, 1913. Serial No. 794,709.

To all whom it may concern:

Be it known that I, CLARENCE E. GRIFFITH, citizen of the United States, residing at Wrights, in the county of Greene and 5 State of Illinois, have invented certain new and useful Improvements in Wrenches, of which the following is a specification, reference being had to the accompanying drawings.

10 This invention relates to an improved wrench and more particularly to a wrench of the chain-grip type which is designed for application to the sprocket wheel of a bicycle or other vehicle to remove the same 15 from the hub.

My invention has for its primary object to produce a simple, efficient and reliable device of the above character which may be easily and quickly applied to the sprocket 20 whereby said sprocket wheel may be turned upon the hub and readily removed with but little manual labor upon the part of the operator.

My invention has for another of its objects to produce a sprocket wrench of the 25 above type which will retain its applied position upon the sprocket wheel and will not slip therefrom upon the application of pressure to the wrench handle, the wrench 30 as a whole being extremely strong and durable and capable of manufacture at small cost.

With the above and other objects in view as will become apparent as the description 35 proceeds, the invention consists in certain constructions, combinations and arrangements of the parts that I shall hereinafter fully describe and claim.

For a full understanding of the invention, reference is to be had to the following description and accompanying drawing, in which

Figure 1 is a side elevation illustrating my improved wrench applied to a sprocket 45 wheel. Fig. 2 is an edge view; Fig. 3 is a section taken on the line 3—3 of Fig. 1; Fig. 4 is a section taken on the line 4—4 of Fig. 1.

Referring in detail to the drawing, 5 designates the shank or handle of my improved wrench which may be of any desired form, but is preferably constructed entirely of steel. At one end of this handle, the same 50 is tapered and bifurcated as indicated at 6, the spaced arms formed by said bifurcation 55 being adapted for engagement upon opposite sides of the sprocket S. The inner or

base wall of the bifurcation 6 is concave as shown at 7 so that the same will not frictionally engage upon the periphery of the sprocket wheel between the teeth thereof in 60 the use of the device. This concave wall or face 7 also provides sharp gripping edges 8 on the handle which engage the periphery of the sprocket wheel at the base of adjacent teeth, as clearly shown in Fig. 1.

To the handle 5 adjacent its bifurcated end, the angularly disposed parallel metal bars 9 are secured, by means of a suitable bolt 10. These bars extend upon opposite sides of the handle and are provided with 65 openings to coincide with the bolt receiving opening formed in the handle. Between the other ends of the parallel bars 9, one end of a link chain 11 is pivotally secured. This chain is of sufficient length to extend approximately half way around the sprocket 70 wheel, the teeth of which are adapted to be received between the parallel link bars of the chain. A heavy leaf spring 12 is adapted to support the chain in position and is 75 disposed closely contiguous thereto. This spring which is of slightly greater width than the link chain is bent in the arc of a circle in its normal condition. One end of this spring is secured to the chain adjacent 80 the end thereof which is attached to the bars 9 by means of a suitable bolt 13, which is disposed between parallel link bars and provided with a clamping nut 14 on one of its 85 ends to securely clamp the end of the spring 90 to the chain. The extremity of the plate 12 is turned around the pin which connects the chain to the ends of the bars 9, whereby pivotal movement of said plate upon the fastening bolt 13 is obviated. Adjacent to the 95 other end of the spring, the same is provided in its longitudinal edges at opposite points with notches or recesses 15. These notches receive the plates 16 of a short link which is pivotally connected to the 100 chain 11 adjacent its end and extends at right angles thereto. To the end link of the chain 11, a link 17 is pivotally connected, said latter link also extending in a plane at right angles to the chain. The links 105 16 and 17 are pivotally connected by the links 18 which are disposed exteriorly of the spring plate 11 or upon the opposite side thereof with respect to the chain 11. These latter links together with the link plates 16 110 serve to effectually prevent separation of the end of the plate 12 from the chain. The end

of the spring plate 12 terminates in a reduced extension 19 which extends between the plates of the link 17. By this manner of connecting the end of the chain to the spring plate, I eliminate all pull or longitudinal strain upon the spring when pressure is applied to the handle 5 to turn the sprocket wheel S.

By referring to the drawing, the manner of application of my invention will be at once understood. In applying the device, the operator grasps the free end of the plate 12 and pulls outwardly upon the same whereby the links of the chain 11 may be engaged upon the periphery of the sprocket wheel S. Upon releasing the end of the spring, said spring contracts against the ends of the sprocket teeth and effectually prevents all liability of disengagement of the link chain therefrom. The bifurcated end of the handle 5 is disposed between adjacent sprocket teeth with the edges 8 in gripping engagement with the periphery of the sprocket at the base of the teeth. Upon now swinging the handle 5 in the proper direction, the sprocket wheel is turned upon the wheel hub and unthreaded therefrom. The sprocket wheel may be as easily applied by simply reversing the illustrated position of the wrench so that the handle will extend upon the opposite side of the sprocket wheel.

From the foregoing, it is believed that the construction and several advantages of my invention will be clearly understood. The device consists of comparatively few parts which are all of simple form and durable in construction. It will therefore be appreciated that the tool may be produced at small manufacturing cost. My improved wrench is capable of easy and quick application to the sprocket wheel and provides means whereby the same may be very easily and quickly removed from the wheel hub or applied thereto with a minimum of labor upon the part of the operator. While I have shown and described the preferred form and construction of the several elements employed, it is to be understood that the invention is susceptible of considerable modification in the form, proportion and arrangement of the parts without departing from the spirit or sacrificing any of the advantages of the invention, as claimed.

Having thus described the invention, what is claimed is:

1. A wrench of the type described comprising a handle, a flexible element connected at one end to said handle and adapted for engagement upon an object, and resilient means mounted upon said element and co-extensive in length therewith to yieldably hold the same in engagement with the object.

2. A wrench of the type described com-

prising a handle, a flexible element connected at one of its ends to said handle and adapted for engagement with an object, and a leaf spring coextensive in length with said element and connected at one of its ends to the handle, said element being attached at its other end to the corresponding end of said spring, whereby the element is yieldingly held in engagement with the object.

3. A wrench of the type described comprising a handle adapted for engagement at one of its ends with an object, a link chain connected at one of its ends to said handle, and resiliently movable means mounted on said chain to retain the links of the chain in engagement with the object.

4. A wrench of the type described comprising a handle provided with means at one of its ends for gripping engagement with an object, a link chain connected at one end to said handle and adapted to extend partially around the object, and a leaf spring permanently secured at one of its ends to said chain and loosely connected at its other end to the end of said chain, said spring acting to yieldingly retain the chain in position upon the object.

5. A wrench of the type described comprising a handle bifurcated at one end, said handle at the inner end of said bifurcation having a concave surface providing gripping edges for engagement with the object, and a link chain connected at one end to said handle and adapted to extend partially around the object and engage the teeth thereof.

6. A wrench of the type described comprising a handle provided with means at one end for gripping engagement with the periphery of an object, a link chain connected at one end to said handle and adapted to extend partially around the object, a curved leaf spring fixed at one end to the chain, and means loosely connected to the other end of said chain and lying upon the opposite side of the spring with respect to said chain to retain the free end of the spring in connection with the end of the chain.

7. A wrench of the type described, comprising a handle, provided at one end with means for gripping engagement with the periphery of a sprocket wheel, a link chain connected at one of its ends to said handle, a curved leaf spring secured at one of its ends to said chain and adapted for engagement with the sprocket teeth to retain the chain links thereon, said spring being provided with notches at its free end, link plates pivotally connected to said chain adjacent its other end and disposed through said notches, an additional link connected to the end of the chain, and links connecting said latter link to the link plates arranged in said notches to loosely connect the end of

the chain to the end of the spring plate, whereby movement of the spring plate with relation to the chain is prevented.

8. A wrench of the type described comprising a handle provided with means at one of its ends for gripping engagement with an object, a flexible element connected at one end to said handle, and adapted to extend partially around the object, and a leaf spring permanently secured at one of its ends to said element and extending the entire length thereof, said chain being of greater width than the flexible element and adapted to yieldably retain the same in position upon the object.

9. A wrench of the type described comprising a handle, provided with means at one of its ends for gripping engagement with an object, a link chain connected at one of its ends to said handle and adapted to extend partially around the object, and a relatively wide leaf spring connected at one

end to the handle and extending the entire length of said chain, said spring yieldably holding the chain in engagement upon the object.

10. A wrench of the type described comprising a handle provided with means at one of its ends for gripping engagement with an object, a link chain connected at one of its ends to said handle and adapted to extend partially around the object, and a leaf spring connected to said handle and extending the entire length thereof, said spring being provided in its other end with notches, and retaining links for said spring connected to the chain and disposed in said notches.

In testimony whereof I hereunto affix my signature in the presence of two witnesses.

CLARENCE E. GRIFFITH.
